UNITED STATES PATENT OFFICE.

WILLIAM SANDERS, OF ST. LOUIS, MISSOURI, ASSIGNOR OF ONE-THIRD
TO J. E. YOUNT AND ONE-THIRD TO E. G. RANKIN, OF ST. LOUIS,
MISSOURI.

CHURN.

No. 830,010.

Specification of Letters Patent.

Patented Sept. 4, 1906.

Application filed May 29, 1906. Serial No. 319,824.

To all whom it may concern:

Be it known that I, WILLIAM SANDERS, a citizen of the United States, residing at St. Louis, in the State of Missouri, have invented 5 certain new and useful Improvements in Churns; and I do hereby declare the following to be a full, clear, and exact description of the invention, such as will enable others skilled in the art to which it appertains to 10 make and use the same, reference being had to the accompanying drawings, and to the letters of reference marked thereon, which form a part of this specification.

This invention relates to new and useful 15 improvements in apparatus for holding receptacles adapted to contain liquids or other material to be agitated, and comprises, essentially, a box which is open upon one side, to the ends of which box are connected the inner ends of springs, one of which is adapted 20 to support the box, while the other is designed to return the same to its normal position after having been raised by the supporting-spring, the outer ends of said springs being secured to fixed objects.

The invention consists, further, in various 25 details of construction and arrangements of parts, which will be hereinafter fully described and then specifically defined in the appended 30 claim.

I illustrate my invention in the accompanying drawings, in which—

Figure 1 is a side elevation of my invention, 35 showing the same in readiness for use; and Fig. 2 is a sectional view centrally through the invention.

Reference now being had to the details of the drawings by letter, A designates a box, which may be of any suitable size or shape, 40 and is provided with an open side A', whereby a receptacle B may be placed within the box or removed therefrom. In each end of

the box is fastened an eye C, and to the eye in the upper end of the box a coil-spring D is fastened, the other end of which is caught over the bracket-arm E, supported from the wall of a building or other object, and a spring D' is fastened to the eye at the lower end of the box and is fastened to a bracket-arm F, also secured to the wall in the same 45 manner as the upper bracket-arm is fastened. Each of said bracket-arms is suitably braced in order to hold the arms rigid. The two springs D and D' are of different strengths, the upper spring being stronger than the 50 lower one for the purpose of counterbalancing the weight of the receptacle or can which is adapted to be placed within the box and also to cause the box, with its receptacle, to be 55 raised up after being depressed by an operator pressing upon the box.

In operation the can or receptacle which holds the cream is placed within the box, and by imparting a downward pressure, by the hand of an operator, upon the box the 60 latter may be caused to vibrate vertically, thereby thoroughly agitating the cream.

What I claim is—

In combination with a box having an open side, an eye secured to the top and bottom of 70 the box, springs of unequal strength, the inner end of each spring secured to one of said eyes and fixed means to which the opposite ends of the springs are fastened, said box adapted to receive a receptacle, which is held 75 upon its seat by the top of the receptacle coming in contact with the under surface of the top of the box, as set forth.

In testimony whereof I hereunto affix my signature in the presence of two witnesses.

WILLIAM SANDERS.
